JOHN J. COUGHLIN, OF BOSTON, MASSACHUSETTS, ASSIGNOR OF THREE-FOURTHS TO DENNIS J. HERN AND JAMES M. PRENDERGAST, BOTH OF SAME PLACE, AND SAMUEL OAKMAN, OF MELROSE, MASS.

ELECTRIC POLICE-CALL ALARM-BOX.

SPECIFICATION forming part of Letters Patent No. 362,477, dated May 3, 1887.

Application filed December 23, 1886. Serial No. 222,427. (No model.)

To all whom it may concern:

Be it known that I, JOHN J. COUGHLIN, of Boston, in the county of Suffolk and State of Massachusetts, have invented new and useful 5 Improvements in Electric Police-Call Alarm-Boxes, of which the following, taken in connection with the accompanying drawings, is a specification.

The object of my invention is to so construct 10 an electric police-call alarm-box that a call-key (which shall identify its user by leaving a numbered portion of itself within the box when withdrawn) may be intrusted to the citizen, it not being a key that will open the box, 15 and to so arrange the interior and the parts connecting with the police-office that an officer is at once notified to call at the box at which the call-key has been used, and there is enabled to communicate with the central office 20 by a system of electric symbols, telegraphic letters, or telephonically, or both. I attain these objects by the mechanism shown in the accompanying drawings, in which—

Figure 1 is a front view of a police alarm-box, the door being represented as open. Fig. 2 is an elevation showing the interior mechanism of the box, the dial-plate A² of Fig. 1 being removed for the purpose of showing the mechanism behind it. Fig. 3 is a cross vertical section showing in detail a part of the mechanism behind the plate of A², Fig. 1. Fig. 4 is a view in perspective showing details. Fig. 5 is a diagram drawn for the purpose of showing the working of my invention. Fig. 6 shows a key in plan, and Figs. 7, 8, and 9 show details of this key.

In the drawings, Fig. 1, A represents the box; A', the door, shown to be open; A³, a key-hole tube, and A² a face-plate or dial for the interior of the box, located as shown in Figs. 1 and 3. This dial A² has upon it first an opening, A⁴, for allowing an entrance for the key. This opening A⁴ coincides with the key-tube A³ on the door when the door is closed. It also 45 has a vertical opening, A⁵, for admitting of the movement of the knob and stem A⁶, (see Figs. 1 and 3,) and also a horizontal opening, A⁷, to admit of the movement of the knob and stem A⁸, Figs. 1, 2, and 3.

50 The knob A⁸, Fig. 1, has a pointer, A⁹, which

the officer may cause to coincide with any of the marks on the dial A², indicated, respectively, by W T, (one star,) (two stars,) (three stars,) or by any other suitable symbols. Attached to the back part of the box is a frame, 55 C. Within this frame C, I have a series, in this case, of six circuit-wheels. The first of these circuit-wheels, C¹, connects with the pen B¹⁰, as shown in Figs. 2 and 3. This wheel C¹ has electrically-contacting points c-----c, 60 which serve to connect the circuit and give the alarm to the police-office. The number of these circuit-connecting points and their arrangement indicate to the office the number 65 of the box from which the call comes.

That part of the disk C² that is not occupied by the number-giving points c-----c is occupied by a circuit-breaking arc of sufficient length to admit the circuit-closing points of the other five circuit-wheels—namely, C³, C⁴, 70 C⁵, C⁶, and C⁷, Fig. 2—to act, as will be herein-after explained.

When the box-number call is made by a citizen, it shall be completed before any one of the circuit-wheels C³-----C⁷ can be put 75 in use by the policeman who opens the door of the box.

The above-described circuit-closing wheels are all attached to a single shaft, C. This shaft has upon it a pinion, C⁸, Fig. 2, which engages 80 with the gear-wheel B⁹ on the shaft B⁶, said shaft B⁶ having motion imparted to it by a coil-spring, B⁸, Figs. 2 and 3. The rapidity of motion imparted by the spring B⁸, through the shaft B⁶ and pinion C⁸, is governed by the 85 escapement-wheel C¹⁰, pallet C¹¹, and balance C¹¹.

The spring B⁸, which, as has been explained, gives motion to the circuit-closing wheels C³-----C⁷, is wound up and limited in its motion by two distinct devices. The first 90 one—that is, the one to be first operated by the key of the citizen—I will now explain.

The crank-arm B⁵, Figs. 2 and 3, is attached to the shaft B⁶, and connected by a link, B⁴, Figs. 2 and 3, to a lever-arm, B³, Fig. 3, to the 95 segment-gear B², Figs. 2 and 3. This segment-gear B² can be moved by the key K, which has upon it a circular rack, K', as shown in Figs. 3, 6, 7, and 9, so that the mere act of pushing the key K into the key-hole A³ A⁴ of the box, 100

as shown in Fig. 3, will cause the movement of the segment-gear B', and thus throw up the arm B', and acting through it, the link B⁴, crank-arm B⁵, and journal B⁶ will wind up the 5 spring B⁸, as desired.

In Fig. 3 I have shown at H a spring, which acts in the same direction upon its connecting parts as the spring B⁸ does, so that, if desirable, one of these springs may be omitted and the 10 operation of the machine remain the same.

The second means of winding up the spring B⁸—that is, the means used by the policeman after he has opened the box—is this: B⁶, Figs. 2 and 3, is a crank-arm attached to the journal B⁶, and connected by a link, B⁷, to the knob and stem A⁸, Figs. 2 and 3. Then by pulling 15 down this knob A⁸ a partial rotation is given to the journal B⁶, and thus the spring B⁸ is wound and the secondary spring H is brought 20 into tension.

The sliding knob A⁶, Figs. 1, 2, 3, and 4, is for the especial use of the policeman after he has unlocked and opened the door, and its construction and use may be explained as follows, 25 (see Fig. 4.) The knob A⁶ is connected by a stem, A⁸, to a yoke-plate, A⁹. This yoke-plate A⁹ embraces the start A¹¹, which is connected at one end to a rocker-shaft, A¹¹, Figs. 4 and 2, and at the other end by an insulation-piece 30 to a spring-lever, A¹⁴. This spring-lever is so bent at its lower end that when the door A', Fig. 1, is closed it will be pushed inwardly, thus causing the shaft A¹¹ to rock in such a manner as to throw out the pen or lever A¹⁰ 35 in such a manner that its point A¹², Fig. 4, will not come in electrical contact with any of the circuit-closing points of any of the circuit-wheels C²—C⁷.

A¹⁷, Fig. 4, is a lever extending downward 40 from the rocker-shaft A¹¹, and terminating in a U-shaped piece, A¹⁰ A¹⁸, the inner upper end of which, A¹⁸, rests against the rear side of a notched rod, A¹⁵, in such a manner as to draw with a spring action the V-shaped piece A¹⁹ forcibly 45 against the notched rod A¹⁵. This pen-lever A¹² A¹⁰ A¹⁷ is so constructed in relation to the V-shaped piece A¹⁹ and the rod A¹⁵ that when not otherwise acted upon it will be out of contact with the points of the circuit-wheels when 50 the V-shaped piece A¹⁹ is at the depression-points of the notches L³—L⁷ and in contact when the V-shaped piece A¹⁹ is at the elevated parts of the notches. The above-described 55 action of the pen-lever A¹⁰ A¹⁷, in connection with the notched rod A¹⁵, is prevented by the overpowering force of the lever A¹⁴ when the door A' is closed—that is, the pressure of the door against the lower end of the lever A¹⁴ will cause the shaft A¹¹ to rock sufficiently 60 (independent of the springing action of A¹⁷) to throw out the pen A¹⁰ A¹² from contact with any of the points of the circuit-wheels.

In Fig. 2, M M represent an ordinary call-bell, of which M' M² are the binding-posts, 65 and M³ M⁴ M⁵ a cut-out device. M⁶ is a start on the link B⁴, which, as the link B⁴ rises or lowers in the upper portion of its path, comes

in contact with the cut-out lever M⁷ and forces it out of function, which will be more fully explained in the description of the system of 70 connecting or wiring.

The device D D³ D⁵ D⁴ D⁶ represents an ordinary polarized magneto call-bell, and, although connected by the same lines that connect the other parts of my invention, is operated 75 by an electro-magneto instrument in the office by the officer in charge. This last-described bell is cut out by the device shown in Fig. 5, in which the two binding-posts D' D² are provided with a cut-out switch, D'. This switch 80 D' is not in contact with the post D², except when the door A' is closed, as indicated by dotted lines at A', Fig. 5, in which case the door presses against the start D³ and forces the switch D' against the post D², thus cutting out 85 the bell D and restoring circuit to the other part of the machine.

The key, K, to be used by the citizen in making the call does not serve to open the door, but to start the circuit-wheels C²—C⁷. By 90 winding up the spring it gives them motion, as has already been set forth. This key is illustrated in Figs. 6, 7, 8, 9, and consists of a shank or handle-piece and a detachable piece, K'. The detachable piece K' is made, as shown, in the 95 form of an annular ratchet, the pitch of the teeth of which corresponds with the pitch of the teeth of the segment-gear B', Fig. 3, so that this key will always act as a ratchet for starting the instrument. The part K' fits loosely upon an extension, K², of the shank K. (See Fig. 8.) This extension K², being smaller than the shank of the key, forms a shoulder against which the part K' may rest while the key is being pushed in and doing its work of winding up the mechanism; but when the shank of the key is pulled out of the box the part K' drops out into the interior of the box, and is there left until the box is opened by the officer. The extreme end K⁴ of the key has 100 stamped or engraved upon it a number—10, for instance—which corresponds with a similar number on the shank of the key, and as record is kept of the name of the person to whom these keys are delivered it is perfectly 105 easy to ascertain the name of the person who gave the citizen's call. The piece K' is returned to the citizen by the officer who unlocks the box.

E and E' represent two telephone-instruments—one in the box and the other, E', in the 110 office.

I will now describe the method of using my invention. The door of the box being closed, as indicated by dotted lines in Fig. 5, causes 115 the lever B' to make a direct circuit between the post D² and D' of the polarized armature-bell D, thus cutting it out of the circuit. Now the citizen, by using his key K, winds up the mechanism and sets the circuit-wheels C²—C⁷ 120 in motion. This same action causes the lever B' to rise and the start M⁶ (after the lever B' has made about two-thirds of its motion upward) to come in contact with the cut-out le-

ver M³, and, throwing it away from the post M⁴, puts the vibrating bell M' into circuit and causes it to ring. This vibrating bell will ring until the lever B⁴ has descended about one-third of its path, at which point the lever M³ will spring back and connect the post M¹ M⁵, thus cutting out the bell and stopping it from ringing.

In some cases it may be desirable to omit the ringing of the bell M', in which case the start M⁶ can be removed from the lever B⁴. As has already been described, the descent of the lever B⁴ is coincident with the rotation of the circuit-wheels C² - - - - C⁷, and as these wheels 15 involve their electric contacting-points make and break the circuit and operate the office-instrument, which may consist of the relay alone, or of a Morse registering-instrument, or of other devices.

20 I will now describe the action of the first circuit-wheel. This circuit-wheel is (as all of the other circuit-wheels) connected to the main battery P by the circuit, (see Fig. 5,) wire W M³ M⁴ W', shaft of the circuit-wheel, C', pen B¹⁰, 25 wire W², wire W³, post D' D², wire W⁵, telephone device E², wire W⁶, wire W⁷, telephone device E³, wire W⁸, wire W⁹, wire W¹⁰, relay P², wire W¹¹, and battery P. Now, as the circuit-wheel C² revolves, its elevations c - - - - c, 30 meeting with the pen B¹⁰, make and break the above described circuit and give the desired alarm to the office, indicating the number of the box from which the alarm comes. That part of the arc of the wheel extending from c² to c³ is not in contact with the pen, thus giving a long dash on the registering-instrument in the office, indicating that the number of the box has been given. That part of the arc of the wheel between the points c⁴ and c⁵ is in contact with the point of the pen B¹⁰, so that the 35 circuit is not broken through the pen B¹⁰ and wire W², and may make and break by the elevations on any of the circuit-wheels C³ - - - - C⁷. All of these wheels C³ - - - - C⁷ are adapted to make contact with the pen A², thus restoring the circuit through W⁴. Upon 40 these circuit-wheels circuit-closing elevations are arranged to return to the office any signal that the officer who has opened the door may 45 desire to send. This he does by pulling down 50

the knob A⁸, thus winding up the spring B⁸, and by moving the knob A⁶ so that its pointer A' shall agree with the symbols on the plate A², as has already been described.

When the officer at the office wishes to communicate by telephone to the officer at the box, 55 he makes a magneto call through the machine X and wires X' and the main-line wires, already described, to the polarized armature-bell D, thus ringing it and notifying the officer to communicate with him by telephone.

I make no claim in this application to the combination of the magneto-call machine X with the wires X' X', that serve to connect the poles of the machine with the main line, as I 60 propose to embody that device in an apparatus which is to be the subject of a future application.

I have described a metallic circuit alone, although a ground-circuit may be used, if 70 desired.

I claim—

1. In a call-box-device key, the combination of the shank and handle K with an annular ratcheted detachable piece, K', operating together substantially as described, and for the purpose set forth.

2. In a call-box device, the combination of the key K, having a detachable ratchet-head, with the segment-ratchet B', arm B³, lever B⁴, 80 crank B⁵, shaft B⁶, and spring B⁸, all operating together substantially as described, and for the purpose set forth.

3. In a call-box, the combination of the door A', spring A¹⁴, start A¹³, and rock-shaft A¹¹, 85 with spring-pen device A¹⁰ A¹² A¹⁶ A¹⁷ A¹⁸ A¹⁹ and the notched rod A¹⁵, all operating together substantially as described, and for the purpose set forth.

4. In a call-box, the combination of the dial-plate A³, knob A⁵, pointer A', post A⁸, and yoke A⁹ with the sliding spring-pen A¹⁰ and A¹² and circuit-wheels C³ C⁴ C⁵ C⁶ C⁷, all operating together substantially as described, and for the purpose set forth.

JOHN J. COUGHLIN.
